CHANGE MAKING OR TOKEN VENDING
MACHINE

Emil de Ryss, Scarsdale, N. Y.

Application March 21, 1930, Serial No. 437,816
Renewed April 17, 1933

1 Claim. (Cl. 194—25)

This invention relates to change making or token vending machines.

It is among the objects of the present invention to provide a novel, simple and improved machine adapted to be coin controlled for the discharge therefrom of a predetermined number of coins or tokens.

A further object of the present invention is to provide in a machine of the character described, a coin arresting device in the coin receiving chute, whereby the coin is retained behind a magnifying glass so that another person may see the coin which the operator has deposited. This coin will be retained in display position until the next operation of the machine.

Another object of the present invention is to provide a device of the character described, in which weighing scales are provided for the purchasing coin, the scales being arranged to operate a change or token delivery mechanism, whereby underweight coins will be prevented from permitting operation of the change delivery mechanism.

A further object of the present invention is to provide in a device of the character described, a novel change or token delivery mechanism, whereby a predetermined number of change coins or tokens may be delivered in response to the deposit within the device of the proper purchasing coin.

A further important object of the present invention is to provide a novel and improved change or token holding receptacle in which coins or tokens may be shipped or conveyed and which may be bodily applied in the machine for predetermined delivery therefrom.

Further important objects of the present invention include the novel structural features, and the combination and interrelation of parts whereby the whole forms a simple and improved structure particularly designed to meet the demands of economic manufacture.

Other objects and the present invention will be apparent from a consideration of the following specification taken in conjunction with the accompanying drawings, in which

Figure 1 is a side elevation partly in section, showing the present invention mounted within a conventional cabinet;

Fig. 2 is a sectional view taken on the line 2—2 of Fig. 1;

Fig. 3 is a detail view of the coin arresting structure with the coin released therefrom;

Fig. 4 is a detail view taken on the line 4—4

of Fig. 1, and illustrating the change or token counting wheel;

Fig. 5 is a sectional view taken on the line 5—5 of Fig. 2, illustrating the operating mechanism of the upper coin counter;

Fig. 6 is a sectional view taken on the line 6—6 of Fig. 2, showing the counting wheel release mechanism;

Fig. 7 is a detail section taken on the line 7—7 of Fig. 1, showing the operation of the slug ejecting device in use with a full sized coin;

Fig. 8 is a similar section showing the ejecting mechanism ejecting a small sized coin;

Fig. 9 is a detail section showing the change coin or token delivery mechanism;

Fig. 10 is a side elevation of the token or change coin reservoir;

Fig. 11 is an end elevation of the reservoir shown in Fig. 10.

By referring more particularly to the drawings, it will be seen that the present invention is illustrated as embodied within a suitable cabinet generally indicated by the numeral 10 in Fig. 1. It will, of course, be understood that the invention is adapted to various structural modifications for adaptation to various types of cabinets and that the type of cabinet herein generally indicated forms no part of the present invention, nor is the invention restricted to the specific structural features thereof, by which it is adapted for mounting within the cabinet of the type here shown.

For receiving purchasing coins, a purchasing coin chute 11 is provided, to which a coin may be delivered through an aperture 12, as shown in Fig. 1. The coin chute 11 is preferably formed, as indicated in Figs. 7 and 8. The coin chute 11, as well as the aperture 12, is so constructed as to prevent passage therethrough of a coin larger than the predetermined size. For ejecting coins smaller than predetermined size from the chute, an ejecting pin 13, as illustrated in Figs. 7 and 8, is provided. Adjacent the ejecting pin 13, the angled side walls of the chute 11 are outwardly turned, the arrangement being such that a coin of proper size will be retained by the side walls and pass on through the chute. A coin of smaller size will, however, be struck by the ejecting pin 13 and canted to the position indicated in Fig. 8, whereby it will be ejected from the chute 11 and thus drop downwardly to be returned to the operator by the delivery trough 14 shown in Fig. 1.

The chute 11 is further provided with a coin arrester, preferably mounted below the ejecting pin 13 and directly behind an aperture 15 of the

front panel of the cabinet 10. The aperture 15 is preferably provided with an enlarging lens 16, whereby a coin retained by the retaining mechanism will be exposed to view. The coin arresting mechanism, as shown in Figs. 2 and 3, includes a pair of intermediately pivoted arms 17, the inwardly extending upper and lower ends 18 of which pass through registering apertures in the side walls of the chute 11. The pivotal point 5 of the arms 17 is near the upper ends of the arms, whereby a synchronical movement of the lower ends 18 is provided upon movement of the upper ends 18. The chute 11 intermediate the ends 18 of the arms 17, is provided with side arresting pins 18^A, the arrangement being such that as a coin passes from the upper ends to the lower ends, it strikes the pins 18^A, which are in staggered relation, thus causing the coin to take a circuitous path, whereby ample time is provided for the 10 closing of the lower ends during the passage of a coin from the upper ends thereof.

In the operation of the coin arrester, it will be seen that the first coin entering the chute will pass between the upper ends 18 of the arms 17, thus moving the arms apart and will come to rest upon the flat upper surface of the lower ends 18 of the arm. The coin thus will be retained in front of the lens 16. When the next coin is deposited, it will strike the upper ends 18, as indicated in Fig. 3, thus pushing the upper ends apart, whereby the lower ends will be moved outwardly to release the first inserted coin therefrom. During the passage of the second coin from the upper ends to the lower ends, ample time is provided for the closing of the lower ends by the arresting pins 18^A, which causes the coin to take a circuitous path and is also provided by the greater length of the arms 17 below their pivot pins. The second coin deposited will then rest upon the upper surface of the lower ends 18, which have moved by gravity to the normal position shown in Fig. 2, as the second coin passes from the upper ends 18 thereto. By this arrangement, it will be seen that the last coin deposited is always retained for view until the next coin takes its place.

The bottom of the chute 11 is provided with a coin-weighing receptacle 20, one side of which is apertured, as at 21, whereby downward movement of the weighing receptacle 20 under the influence of a coin received thereby, will bring the aperture 21 into registration with a receiving chute 22, which leads to a suitable purchasing coin receptacle located within the cabinet. The bottom inclined surface of the receptacle 20 is provided with a pair of downwardly extending rods 23, the lower end of which rests upon a releasing arm 24, which normally rests in the horizontal position shown in Fig. 2, thus holding the receptacle 20 in the position indicated. The reception of a coin by the receptacle is adapted to tilt the releasing arm 24 to release the change coin mechanism as will be hereinafter described.

65 For controlling the release of a predetermined number of change coins or tokens from the device, an operating shaft 25 is provided, the forward end of which extends through the front panel of the cabinet 10 to be provided with a suitable operating handle as indicated at 26.

70 Mounted upon the shaft 25, a counting wheel release mechanism including a disk 27 is provided, from one face of which projects a controlling pin 28. The shaft 25 and thus the disk 27, is adapted for clockwise rotation as indicated in Fig. 2. The pin 28 normally rests against a stop 29 carried

75

by the releasing arm 24. The arm 24 is pivoted as at 30, one end of the arm resting under the rods 23 of the scales 20, while the opposite end of the arm extends adjacent the disk 27. When a coin is received on the scales 20, the rods 23 are depressed, thus depressing the short end of the arm 24. The opposite end moves upwardly whereby the pin 28 will pass downwardly through a recess 28^A of the arm 24. The disk is thus free to be turned by the revolution of the shaft 25, and in such turning the pin moves under and upwardly on the opposite side of the stop 29, through the recess 28^A. When the disk 27 has made one complete revolution, it will be seen that the pin 28 depresses the longer end of the arm 24, bringing the same to normal position as shown in Fig. 2, thereby raising the scales 20 to normal position, and by engaging the stop 29 retaining the shaft 25 against further rotation.

For counting out the proper predetermined number of change coins or tokens delivered by the apparatus after the insertion of one purchasing coin, the counting wheel 32 is mounted upon the shaft 25 for rotation therewith. As indicated in Fig. 4, the wheel 32 is in registration with a change coin or token chute 33. The wheel 32 is further provided with a plurality of coin or token receiving pockets 34, the arrangement being such that as the shaft 25 is rotated through one complete revolution, each of the pockets 34 is brought to registration with the chute 33; thus a coin from the chute is received in each of the pockets, which by further rotation drops the coins therefrom to the delivery trough 14. The arrangement is normally such that only the predetermined number of coins as controlled by the number of pockets in the wheel, will be delivered by a single revolution of the shaft 25.

For delivering coins or tokens to the chutes 33, a reservoir 35 is provided as illustrated in detail in Figs. 10 and 11. The receptacle 35 is provided with a removable closure 36 at one end, which is adapted to be removed to provide for the insertion of coins in the reservoir. From the body of the reservoir, an axle 37 extends through the closure 36 and is receivable through a suitable bearing 38, as indicated in Fig. 1. The opposite end of the reservoir is also provided with a centrally apertured removable closure 39. The lower closure 39 is formed of a pair of associated semi-circular members, as indicated in Fig. 11, suitable thread securing means 40 being provided for securing the sections together around the lower end of the reservoir 35. The outer cylindrical body of the reservoir 35 is preferably formed of glass or the like and an internal removable body 41 is provided which is formed with a corrugated outer surface, the edges of the corrugations abutting the inner face of the cylindrical body, whereby coin receiving recesses of substantially elliptical form are provided. In view of the cross section of the recesses, it will be seen that coins therein will extend at an angle with respect to the axis of the reservoir, preferably at about forty-five degrees. As indicated in Fig. 9, this arrangement provides for the coins in the lower side of the reservoir to lie substantially horizontal with respect to the cabinet while the coins in the upper recesses of the reservoir stand substantially vertical. The internal body 41 is provided with end closures 42, as seen in Fig. 9. From the upper closure, the upper axle 37 extends, and from the lower one, as shown in Fig. 9, an angular projecting axle 43 extends. The ends of the reservoir are normally opened, being 11

closed for shipment or transportation of coins therein, by the removable cover 39. The pin 43 extends through the central aperture of the cover 39, and is adapted to be received within a corresponding angularly recessed rotating support 44. The bottom of the receptacle is adapted to lie upon a suitably inclined table 45. By the angular relation of the coins in the recesses 41, it will be seen that only one corner of the edge 10 of the coins in the inactive recesses, bears against the table 45, thus elimination of unnecessary friction is provided.

In the operation of the device, a loaded reservoir of coins with the cover 39 in position, is mounted upon the table 45, its upper axle 37 extending within the bearing 38, while its lower axle 43 is received within the support 44. The securing means 40 is then loosened and the sections of the cover 39 are removed, thus to permit further downward movement of the reservoir on to the table 45, whereby the coins of the recesses 41 will rest upon the table 45. One portion of the table 45 is cut away to provide for registration of a coin delivering chute 46 with one of the recesses 41. As seen more clearly in Fig. 9, coins are adapted to drop from the registering recesses 41 into the chute 46. Due to the vertical position of the coins in the upper recess 41, as hereinbefore described, it will be seen that they may continue such vertical position as they pass from the recess 41 to the chute 46, from which they pass into the chute 33, as will be hereinafter described.

For insuring the proper number of coins delivered from the wheel 32, an upper coin counter is positioned at the juncture of the chutes 46 and 33. The coin counter includes a slidable plate 47 mounted in the upper end of the chute 33, its normal position being such that it blocks the entrance of coins from the chute 46 to the chute 33. For operating the plate 47 the proper number of times, thus permitting the proper number of coins to enter the chute 33, an operating arm 48 is provided thereon. The arm 48 extends downwardly for connection through a connecting medium 49, with a vertical operating arm 50, the lower end of which rests upon a pivoted plate 51, as shown in Fig. 2. The plate 51 is prevented from downward dropping movement by resting upon a projection 52 of a disk 53 mounted for rotation with the shaft 25. The plate 51 is provided with a cut-out portion 54, whereby rotation of the disk 53 in the direction of the arrows in Fig. 2, will move upwardly the plate 51 until the projection 52 registers with the recess 54 and passes therethrough. This movement will raise the plate 47 which will drop down by gravity as the plate 51 drops down to rest upon the next projection 52 of the disk 53. By this arrangement, it will be seen that as the shaft 25 is rotated, the arm 50 will be reciprocated, thus to count coins

from the chute 46 into the chute 33. It will further be seen that this construction prevents reverse rotation of the shaft 25 as upon such rotation the pin 52 will be moved backwardly and will strike the upper surface of the plate 51, thus preventing further backward rotation.

For rotating the reservoir 35 so that when one of the recesses is exhausted of coins the next one will be moved to registering position with the chute 46, a gear 55 is provided on the rotating shaft of the support 44. The gear 55 is adapted for rotation by association with a driving gear 56, upon the shaft of which a bevel gear 57 is mounted. For driving the bevel gear 57, a mutilated gear 58 is provided, which is driven through a shaft 59, by a chain 60 associated with a sprocket 61 mounted upon the shaft 25, as indicated in Fig. 1. The arrangement will be seen to be such that continuous rotation of the shaft 59 will impart periodic fractional rotation to the gears 55 and 56. The gearing arrangement is of such timing that sufficient revolutions of the shaft 25 are permitted before rotation of the reservoir 35, to provide for the complete discharge of coins from the recess 41, which is at that time 100 registering with the chute 46. By this arrangement, all the coins of one of the recesses 41 may be delivered to the chute 46 before rotation of the reservoir to bring into registration with the chute 46, a different recess 41.

From the foregoing it will readily be seen that the invention provides a novel, simple and improved mechanism, whereby the insertion of a coin of proper size and weight will release a coin counting and delivery mechanism to deliver a predetermined number of change coins or tokens to the operator. The numerous novel and improved structural features herein presented are obviously not confined to the specific presentation thereof, and numerous changes, modifications and the full use of equivalents may be resorted to without departing from the spirit or scope of the invention as outlined in the appended claim.

What is claimed is:

In a coin controlled device, the combination of a coin chute, means responsive to the weight of a coin delivered to said chute, a pivoted lever having a slot and an abutment adjacent each other, a rotatable member, an eccentric pin 125 thereon normally engaging the lever abutment for locking said member against rotation, and connections between said lever and said means whereby the former is tilted by the latter in response to the weight of the coin to move said 130 abutment out of contact with said pin and release the pin through the lever slot, said pin engaging said lever at another point thereon upon rotation of said member to restore said lever and means to normal position.
